ATTORNEY.

UNITED STATES PATENT OFFICE

WALTER EDWARD SMITH, OF PROVIDENCE, RHODE ISLAND, ASSIGNOR TO KENNEY MANUFACTURING COMPANY, OF CRANSTON, RHODE ISLAND, A CORPORATION OF RHODE ISLAND

DESIGN FOR A DRAPERY ROD

Application filed February 24, 1931. Serial No. 38,804. Term of patent 14 years.

To all whom it may concern:

Be it known that I, WALTER EDWARD SMITH, a citizen of the United States, residing at Providence, in the county of Providence and State of Rhode Island, have invented a new, original, and ornamental Design for Drapery Rod, of which the following is a specification, reference being had to the accompanying drawings, forming part thereof.

Fig. 1 is a fragmentary view as seen from

the inside or rear of a drapery rod showing my new design.

Fig. 2 is an elevation of a complete rod, and

Fig. 3 is a fragmentary view of such rod as seen from the front or outside.

I claim:

The ornamental design for a drapery rod, as shown.

WALTER E. SMITH.
